ATTORNEYS

UNITED STATES PATENT OFFICE.

WILLIAM H. LUDWIG, OF CHAMBERSBURG, PENNSYLVANIA.

DESIGN FOR A NAPKIN-RING.

SPECIFICATION forming part of Design No. 21,186, dated December 1, 1891.

Application filed October 13, 1891. Serial No. 408,735. Term of patent 3½ years.

To all whom it may concern:

Be it known that I, WILLIAM H. LUDWIG, a citizen of the United States, residing at Chambersburg, in the county of Franklin and 5 State of Pennsylvania, have invented and produced a new and original Design for Napkin-Rings, of which the following is a specification.

The leading feature of my design consists 10 in the ring simulating in its configuration and ornamentation a napkin folded into open or ring-like form.

The minor feature consists of the fringe-like ornamentation *a*, simulating the fringe of 15 a napkin, and the somewhat-pointed elongation *b* at one end, the lines whereof curve from the extreme end *c* inward to the ring

proper *d*. The pointed end simulates one angle of a triangularly-folded napkin, the ring at the opposite end or ring proper *d* simulating the remaining overlapped angles, the outer one of which is represented as fringed. 20

The ornamental lines *e* shown represent the woven figure or pattern of a napkin, and the letter *f* indicates a figure representing a pin, 25 as if uniting the overlapped ends.

I claim—

The design for a napkin-ring, as herein shown and described.

WILLIAM H. LUDWIG.
